CLAIM

The ornamental design for a tubing component, as shown and described.

DESCRIPTION

FIG. 1 is a perspective view of a tubing component showing our new claimed design in accordance with a first embodiment;

FIG. 2 is another perspective view thereof;

FIG. 3 is a bottom plan view thereof shown in an alternate environment of use;

FIG. 4 is a top plan view thereof;

FIG. 5 is a left-side elevational view thereof, the right-side elevational view being a mirror image of the left-side elevational view;

FIG. 6 is a back elevational view thereof;

FIG. 7 is a front elevational view thereof;

FIG. 8 is a perspective view of the tubing component in accordance with a second embodiment.

FIG. 9 is another perspective view thereof;

FIG. 10 is a bottom plan view thereof shown in an alternate environment of use;

FIG. 11 is a top plan view thereof;

FIG. 12 is a left-side elevational view thereof, the right-side elevational view being a mirror image of the left-side elevational view;

FIG. 13 is a back elevational view thereof; and,

FIG. 14 is a front elevational view thereof.

The broken lines in the figures depict portions of the tubing component that form no part of the claimed design.
